RADIATOR-CASING.

1,301,419.

Specification of Letters Patent. Patented Apr. 22, 1919.

Application filed November 20, 1916. Serial No. 132,462.

To all whom it may concern:

Be it known that I, WESTON M. FULTON, a citizen of the United States of America, and a resident of Knoxville, Tennessee, have 5 invented a new and useful Improvement in Radiator-Casings, which invention is fully set forth in the following specification.

This invention relates to heat-regulating devices, and more particularly to radiator casings in which thermosensitive means, subject to room temperature, is used for automatically operating dampers for controlling the flow of heated air through the casing.

In my Reissue Patent No. 14,309, dated 15 June 5, 1917, I have disclosed a radiator casing wherein the thermosensitive means is positioned within a downwardly directed conduit communicating adjacent its upper end with the room, and communicating adjacent its lower end with an upwardly directed passage in direct heat-interchanging relation with the end-section of the radiator, whereby, owing to the heating influence exerted by the radiator on the air in said 20 passage, a circulation is maintained over the thermosensitive means. To secure the most efficient operation where the radiator end-section constitutes the separating means between the main radiator-receiving portion 25 of the casing and said passage, this radiator section must be of the same size as the interior cross section of the casing and constitute a partition closing communication between said passage and the portion of the casing 30 inclosing the main radiator sections. This necessitates the employment of a special end-section in the form of a hollow plate or wall conforming to the interior of the casing. It is an object of this invention to provide a 35 radiator casing, having an air-passage in heat-interchanging relation with the radiator whereby to induce a circulation of air over thermosensitive means mounted in a conduit communicating with said passage, 40 which may be used with any radiator without respect to the type of end-section employed thereby.

Another object of this invention is to provide a device of the type characterized 45 wherein there is an air passage in heat-interchanging relation with the radiator, but closed against communication with the interior of the main radiator-receiving portion of the casing, without necessitating a casing 55 that closely fits the end section of the radi-

ator, whether a special end-section be employed or not.

A further object of this invention is to provide a device of the type indicated that may be inexpensively constructed in stock 60 sizes and applied to any type of radiator, provision being made for any lack of perpendicularity of the end-section of the radiator to the floor of the room in which it is placed. 65

Further objects relate to the provision of radiator casings that are simple in construction, easy of installation and efficient in operation.

Stated broadly, the invention comprises, 70 in combination with a radiator, a casing therefor having dampers for controlling the flow of heated air therethrough, thermosensitive means operatively connected to said dampers for actuating the same, a conduit 75 through which a circulation of air is induced and within which current said thermosensitive means is positioned, said conduit being open to the room, preferably adjacent its upper end whereby it receives air 80 at a level intermediate the upper and lower strata of air in the room with which it communicates, and an air-passage with which said conduit communicates and which is in heat-interchanging relation with the radiator to induce a circulation of air over said 85 thermosensitive means, one wall of said passage comprising a heat-conducting partition in heat-interchanging relation with said radiator and, by preference, in contact therewith. Said conduit and passage are shown as provided in an extension of the casing proper, and the conduit is insulated from the heating influence of said radiator, heat-conducting partition and passage. 90 95

The invention is capable of receiving a variety of mechanical expressions, one of which is shown on the accompanying drawings, but it is to be expressly understood that the drawings are for the purpose of 100 illustration only, and are not to be construed as a definition of the limits of the invention, reference being had to the appended claims for that purpose.

Referring to the drawings, wherein the 105 same reference characters indicate corresponding parts in the several figures.

Figure 1 is a horizontal sectional view of an end portion of a radiator-casing embodying the present invention; 110

Fig. 2 is a vertical sectional view of the structure shown in Fig. 1;

Fig. 3 is an elevation of a preferred form of radiator end-section to be used with the 5 present invention, also showing a cross section therethrough;

Fig. 4 is a face and end view of a heat-conducting wall suitable for use with an end-section as shown in Fig. 3;

10 Fig. 5 is an elevation and plan of a modified form of radiator end-section; and

Fig. 6 is a face and end view of a heat-conducting wall suitable for use with an end-section as shown in Fig. 5.

15 Referring in detail to said drawings, 1 represents a plurality of radiator sections of any preferred type, and 2 a casing for inclosing the same. The upper portion of the radiator-inclosing portion of said casing is 20 provided with damper-controlled openings for regulating the flow of heated air through said casing. In the form shown (Fig. 2), the casing is provided with a hood 3, and openings 4 are provided in the wall separating the radiator-inclosing portion from said hood, said openings being controlled by dampers 5 pivotally connected to an operating link 6.

Said casing 2 in the form shown is 30 provided with an extension 7, the hood also preferably extending over the top of said extension. Within this extension a vertical depending partition 8, which terminates just above the floor 9 of said extension, divides 35 the interior thereof into two communicating compartments 10 and 11. The compartment 10, which constitutes a downwardly directed conduit, is provided with an inlet opening 12, preferably adjacent its upper end where- 40 by it receives air at a level intermediate the upper and lower strata of air in the room with which it communicates. While this compartment is herein designated a conduit, it is to be understood that the term is used 45 as generic to any suitable inclosure through which air may be drawn to pass over a thermosensitive device in operative relation thereto. Compartment 11, which constitutes an upwardly directed air passage, is pro- 50 vided with an exit opening 13 adjacent its upper end, shown as provided in the wall separating the extension 7 from the hood 3. These compartments are in communication adjacent their lower ends, as by the opening 55 14 left between the end of partition 8 and the floor 9, said opening constituting an outlet for conduit 10 and an inlet for passage 11.

To separate air-passage 11 from the radiator-containing portion of the casing, a wall 60 15 of heat-conducting material is mounted in heat-interchanging relation with the end-section of the radiator. This wall is preferably of such size and shape as to close communication between the interior of the main 65 portion of the casing and the passage, and,

by preference, is supported in contact with the end-section of the radiator. Any usual or preferred form of radiator end-section may be used, two types being shown on the drawings. The preferred construction (Fig. 70 3) comprises a generally rectangular, im- 75 perforate, hollow plate or wall 16, and when such an end-section is employed, wall 15 may be flanged or bent angularly along its side edges, as shown at 17, to conform with 75 the shape of and to embrace the side edges of said section. This wall may be positioned in engagement with the end-section by slipping the same longitudinally over such section. If desired, however, an end-section 80 16' of the more common type shown in Fig. 5 may be employed, in which event the heat-conducting wall may be flanged or bent along its side edges, as shown at 17' in Fig. 6, to conform with the shape of and to em- 85 brace the side edges of said section, so that the same may be slipped into position longitudinally thereof. Although not entirely necessary if wall 15 fits the interior cross-section of the casing 2, means are preferably 90 provided for mounting or positioning said wall within said casing, said means also preferably providing for any lack of perpendicularity of the end-section of the radiator to the floor of the room. In the form 95 shown flanged members 18 are secured to the wall 15 adjacent its edges in any suitable way, as by riveting or spot welding, said flanged members preferably extending throughout the length of said wall. The 100 flange of each of said members provides an inwardly directed locking edge, as shown at 19, to interlock with flanged members 20 suitably attached to the inner faces of the walls of the casing and preferably extending 105 throughout the length of wall 15, said members 20 each providing a longitudinal groove and terminating in an outwardly 110 directed locking edge as shown at 21. These interlocking members constitute a slip-connection 110 permitting a limited angularity therebetween.

Positioned in the current of air flowing through said conduit is any suitable thermosensitive device 22, the same being preferably 115 mounted in said conduit and shown as concealed therein. Said thermosensitive device is provided with an operating stem 23 which extends through the partition 8 and is pivotally connected to a lever 24 operatively connected to the damper-operating link 6.

To protect the conduit 10 and thermosensitive device from the heating influence of the radiator, wall 15 and passage 11, partition 125 8 is made non-heat-conducting in any similar way, as by constructing the same of sheet metal lined with cork or other heat-insulating material; floor 9 is also preferably made non-heat-conducting in a similar way; the 130

top of said conduit is covered with heat-insulating material, as shown at 25; and the walls of the conduit are insulated from the walls of the casing proper, so as to prevent conduction of heat therebetween, as by flanging the walls of said casing and the extension 7, as shown at 26, and interposing any suitable heat-insulating material 27.

In operation, the end radiator-section 16 heats the partition 15 which in turn heats the air in the upwardly directed passage 11. This air rises and passes freely into the room through the outlet opening 13. Air is drawn in through inlet 12 of conduit 9 and, passing over thermosensitive device 22, enters the passage 11. The thermosensitive device, subjected in the form shown to air from a level whereby it represents average room-temperature, responds to the temperature thereof and operates the dampers 5 through the intermediate connections, controlling the flow of heated air through the main portion of the casing 2. The heat-insulating partition 8 protects the thermosensitive device from the direct radiation of the heat-conducting wall 15; the heat-insulating floor 9 protects said device from convection currents rising from the lower portion of the radiator; the insulating wall 25 protects said device from the heating influence of the air in the hood; and the insulating strips 27 protect said device from heat conducted along the walls of the casing to the extension.

By the provision of a heat-conducting wall of the type illustrated at 15, it will be perceived that the air-passage 11 is separated from the main radiator-containing portion of the casing irrespective of the type of radiator end-section employed and any lack of conformity between the cross-sections of the radiator and casing, and the thermosensitive device is subjected to air at room-temperature by a circulation maintained independently of the air in the radiator-inclosing portion of the casing. By providing said wall with bent portions, as shown at 17, the same may be readily slipped into position longitudinally of the radiator-section, and by the use of the interlocking members 18 and 20 a slip-connection is provided between said wall and the walls of the casing, which enables assemblage by engaging the locking edges 19 in the grooves provided by the members 20 and sliding the same longitudinally therein, and which permits said wall to engage the radiator section closely although assuming a position out of perpendicular to the floor of the room.

While the illustrated embodiment has been described with considerable particularity, it is to be expressly understood that the invention is not to be restricted to the construction shown upon the drawing, for it is capable of receiving a variety of mechanical

expressions, some of which will readily suggest themselves to those skilled in the art, while certain features thereof are capable of use without other features thereof. Reference is therefore to be had to the appended claims for a definition of the limits of said invention. 70

What is claimed is:

1. In combination, a radiator, a casing therefor, dampers controlling the circulation of air through said casing, an air-passage having an outlet opening adjacent its upper end, one wall of said passage comprising a plate of heat-conducting material supported in contact with said radiator, a conduit in communication with said passage, and thermosensitive means in the current of air flowing through said conduit and operatively connected to said dampers. 75

2. In combination, a radiator, a casing therefor, dampers controlling the circulation of air through said casing, an air-passage having an outlet opening adjacent its upper end, one wall of said passage comprising a plate of heat-conducting material in contact with said radiator, a conduit in communication with said passage, means insulating said conduit from the heating influence of said radiator and passage, and thermosensitive means in the current of air flowing through said conduit and operatively connected to said dampers. 80

3. In combination, a radiator, a casing therefor, dampers controlling the circulation of air through said casing, an air-passage having an outlet opening adjacent its upper end, one wall of said passage comprising a plate of heat-conducting material supported in contact with said radiator, a conduit in communication with said passage, means insulating the walls of said conduit from the walls of said casing, and thermosensitive means in the current of air flowing through said conduit and operatively connected to said dampers. 85

4. In combination, a radiator, a casing therefor, dampers controlling the circulation of air through said casing, a partition of heat-conducting material substantially co-extensive in width with the interior cross-section of said casing, said partition being in heat-interchanging relation with said radiator and dividing the interior of said casing into a radiator-receiving compartment and a second compartment, an air-passage in said second compartment having an outlet adjacent its upper end and in heat-interchanging relation with said partition, a conduit in communication with said passage, and thermosensitive means in the current of air flowing through said conduit and operatively connected to said dampers. 90

5. In combination, a radiator, a casing therefor, dampers controlling the circulation of air through said casing, a partition of

110

115

120

125

130

- heat-conducting material substantially co-extensive in width with the interior cross-section of said casing, said partition being in heat-interchanging relation with said radiator and dividing the interior of said casing into a radiator-receiving compartment and a second compartment, an air-passage in said second compartment having an outlet adjacent its upper end and in heat-interchanging relation with said partition, a conduit in communication with said passage, means insulating said conduit from the heating influence of said radiator and passage, and thermosensitive means in the current of air flowing through said conduit and operatively connected to said dampers.
6. In combination, a radiator, a casing therefor, dampers controlling the circulation of air through said casing, an air-passage having an outlet opening adjacent its upper end, a plate of heat-conducting material separating the radiator-receiving portion of said casing from said passage, said plate having flanges coacting with the radiator and maintaining said plate in heat-interchanging relation with said radiator, a conduit in communication with said passage, and thermosensitive means in the current of air flowing through said conduit and operatively connected to said dampers.
7. In combination, a radiator, a casing therefor, dampers controlling the circulation of air through said casing, an air-passage having an outlet opening adjacent its upper end, a plate of heat-conducting material separating the radiator-receiving portion of said casing from said passage, interlocking flanges on said plate and casing positioning said plate in heat interchanging relation with said radiator, a conduit in communication with said passage, and thermosensitive means in the current of air flowing through said conduit and operatively connected to said dampers.
8. In combination, a radiator, a casing therefor, dampers controlling the circulation of air through said casing, an air-passage having an outlet opening adjacent its upper end, a plate of heat-conducting material separating the radiator-receiving portion of said casing from said passage, interlocking flanges on said plate and casing constituting a slip-connection and positioning said plate in heat-interchanging relation with said radiator, a conduit in communication with said passage, and thermosensitive means in the current of air flowing through said conduit and operatively connected to said dampers.
9. In combination, a radiator, a casing therefor, dampers controlling the circulation of air through said casing, an air-passage having an outlet opening adjacent its upper end, a plate of heat-conducting material separating the radiator-receiving portion of said casing from said passage, flanges on said

plate coacting with the radiator and interlocking flanges on said plate and casing for positioning said plate in heat-interchanging relation with the radiator, a conduit in communication with said passage, and thermosensitive means in the current of air flowing through said conduit and operatively connected to said dampers.

10. In combination, a radiator, a casing therefor, dampers controlling the circulation of air through said casing, an air passage having an outlet opening adjacent its upper end, a wall of said passage comprising a plate of heat-conducting material supported in contact with said radiator, a conduit in communication with said passage and in non-heat-interchanging relation with said radiator and passage, and thermosensitive means in the current of air flowing through said conduit and operatively connected with said dampers.

11. In combination, a radiator, a casing therefor, dampers controlling the circulation of air through said casing, an air-passage having an outlet opening adjacent its upper end, a plate of heat-conducting material separating the radiator-receiving portion of casing from said passage and provided with means whereby the same may be supported from said radiator in heat-interchanging relation therewith, a conduit in communication with said passage, and thermosensitive means in the current of air flowing through said conduit and operatively connected to said dampers.

12. In combination, a radiator, a casing therefor, dampers controlling the circulation of air through said casing, an air-passage having an outlet opening adjacent its upper end, a plate of heat-conducting material separating the radiator-receiving portion of said casing from said passage, said plate and casing being provided with interengaging members whereby said plate may be supported in heat-interchanging relation with said radiator, a conduit in communication with said passage, and thermosensitive means in the current of air flowing through said conduit and operatively connected to said dampers.

13. In combination, a radiator, a casing therefor, dampers controlling the circulation of air through said casing, an air-passage having an outlet opening adjacent its upper end, one wall of said passage comprising a plate of heat-conducting material mounted on said radiator and coacting with said casing to separate said passage from the radiator-receiving portion of said casing, said plate being in heat-interchanging relation with said radiator and passage, a conduit in communication with said passage, and thermosensitive means in the current of air flowing through said conduit and operatively connected to said dampers.

14. In combination, a radiator, a casing therefor, dampers controlling the circulation of air through said casing, an air-passage having an outlet opening adjacent its upper end, one wall of said passage comprising a separate, readily positioned plate of heat-conducting material coacting with said casing to constitute a partition between said passage and the radiator-receiving portion 10 of said casing, said plate being in heat-interchanging relation with said radiator and passage, a conduit in communication with said passage, and thermosensitive means in the current of air flowing through said conduit and operatively connected to 15 said dampers.

In testimony whereof I have signed this specification.

WESTON M. FULTON.
